PEG SCOREBOARD

Jesse W. Richardson, Philadelphia, Pa.

Application June 10, 1947, Serial No. 753,789

5 Claims. (Cl. 235—90)

1

This invention relates to a score board and more particularly relates to a universal peg score board which is particularly adapted to keep score for any of numerous card games which are scored in a different manner from each other.

An object of this invention is to provide a peg score board which provides means for keeping the score of any one of numerous card games which have different methods of scoring.

Another object of my invention is the provision of a score board in which sockets for the reception of the pegs for indicating the scores for four players are so grouped that the score of each player can readily be counted by the positions of a peg or pegs in the section allotted to an individual player or to partners.

Another object of my invention is to provide a plurality of groups of sockets in each section, each comprising groups of columns spaced from each other, as well as groups of rows in the columns separated from each other, each row being designated by a numeral from 1-0 between two groups of columns of sockets, thus providing a group of columns of sockets on each side of the designating numerals for two types of scores in the players allotted section.

Referring to the drawings, in which:

Fig. 1 is a plan view of the kit when the cover is in position for scoring;

Fig. 2 is a longitudinal sectional view on the line 2—2 of Fig. 1; and

Fig. 3 is a transverse sectional view on the line 3—3 of Fig. 1 with the cover reversed from the position shown in Figs. 1 and 2.

In the drawings, the reference character 10 designates the container having a bottom 12, side members 14, end members 16 and 18 and a cover 20.

The cover is provided with a tongue 22 along each side edge which is spaced intermediate the faces thereof and are arranged to slide in grooves 22' in the side members 14, one face of the cover is provided with a series of peg sockets 24 for scoring as hereinafter described.

The container or box is of a size to receive several decks of playing cards 30 in a cover or covers as well as a peg holder 32 having sockets for the reception of the reduced ends of pegs 34 used for seating in the sockets 24 in one face of the cover 20 to indicate the score.

The pegs may be of various colors or other differentiating means designating different values or different players.

When a game is in progress the cover may be removed from the container 10 or reversed in

the grooves as shown in Figs. 1 and 2, the container forming a support or stand for the score board to elevate the board above the table.

The arrangement of the sockets in the score board is such as to provide four sections N, E, W and S with an arrow pointing toward each section, each section comprising six longitudinal columns of sockets each having ten transverse rows of sockets.

10 The columns designate units, tens, hundreds, thousands, tens of thousands and hundreds of thousands and may be read in either direction with relation to the longitudinal center of the board. I preferably number the rows in the columns 1, 2, 3, 4, 5, 6, 7, 8, 9 and 0, using all the digits in sequence and preferably provide a space between the hundreds and thousands columns for numbering the rows and also preferably provide a space between rows 5 and 6 so that the values indicated by the placed pegs can readily be ascertained.

When the board is specifically marked for a cribbage score board, an arrow points upwardly at the bottom of each of the units, hundreds and tens of thousands columns of sections S and W while similar arrows point downwardly from above the tens, thousands and hundreds of thousands columns of sections E and N to indicate the consecutive positioning of the pegs during 25 the scoring, that is, up one column and down the next, in other words, counting is done upwardly in alternate columns of two sections and downwardly in the other columns.

When desired, the results of the positioned pegs in the different sections may be read across the rows. For example, a peg has been positioned in each of the six columns of section S designating a value of 122,430 when read from the longitudinal center of the board.

30 As above described, a value totaling 999,999 is indicated when a peg is placed in each socket in row 9 of any of the six columns of either of the sections N, E, S and W.

The numbering of the rows in sections N and W is the same as in the rows of sections S and E, but the arrows are in the reverse order.

It will be appreciated that, if desired, the numbering of the rows in sections N and W may be the reverse of those in sections E and S.

50

Cribbage

The score board is provided with an additional socket at the end of the sixth column of sockets in sections E and S designated A, as well as a 55 similar socket B at the end of the sixth column

of sections N and W to represent the final score of 121 when used for scoring cribbage.

When used for cribbage scoring, the dealer starting the game begins scoring from line 1 in the extreme right column in section S, while the opponent starts from the extreme left column from row 1 in section W, both scoring by moving their pegs from the outer to the inner rows, reversing the directions of movement of the pegs in alternate rows. For example, the dealer's present score being sixty, the previous score was fifty-five as indicated by the pegs in section E, the opponent's present score being forty-seven, the previous score being forty-one as indicated by the pegs in section W. The crossed arrows indicate the ninetieth socket of each player when playing cribbage.

The lower row of sockets below the sections S and W are adapted for scoring games won by contestants, and, in order to differentiate, each contestant may use pegs differing in color or shape from those of the other contestant.

Bridge

When using the score board for scoring bridge games, N and W sections are used by one team and E and S sections are used by the other team. Two sets of pegs, each differing in color or shape from the other, being used by each team, each player using pegs differing from those of the other for indicating the score in the players' section. The rubber scoring being indicated by placing a peg for each rubber won in the sockets below sections S and W.

To indicate side vulnerable, a peg should be placed in the socket immediately below the scoring sections S or W, or the sockets A and B used for indicating the score of 121 when playing cribbage.

Gin Rummy

When playing gin rummy, one contestant, say contestant A, scores on section S, the other, say B, on section W. The scores are indicated on the three columns at the right of the numerals designating the rows, while the boxes are scored on the three columns at the left of the numerals. A score of nine hundred and ninety-nine can be indicated on the three scoring columns and the same number can be indicated on each of the columns for scoring the boxes in each section.

For example, the pegs in section S show that contestant A has a score 430 and a total of 122 boxes when read from the longitudinal center of the board.

The scoring for contestant B would be designated by pegs in a similar manner.

Rummy is scored in the same manner as gin rummy only no box score is made.

Pinochle

In pinochle, the scoring is the same as in gin rummy, one set of partners scoring on section S, the other set scoring on section W. The scoring being indicated on the same columns as in gin rummy, while minus scoring is indicated in the three columns at the left of the numerals.

A three handed game can be played by the third party using section E for scoring.

Poker

The score of a two, three or four handed game of poker can be scored on the board, each player scoring on a section E, S, W or N.

The indebtedness of the pot to the player being indicated on the three columns on one side of

the columns of numerals, while the indebtedness of the player to the pot is indicated on the three columns on the other side of the column of numerals.

5 The advantages of my invention result from the provision of a game kit comprising a container having a reversible cover with score receiving peg sockets in one face, space in the container for several decks of cards and a removable holder for a plurality of scoring pegs of different characteristics such as shapes, size or color, each being provided with a stem adapted to seat in any of the sockets for indicating the score of players or contestants of various card games.

10 15 Another advantage of my invention results from the provision of a score board divided into four sections, each section being designated for an individual player, each section being divided into at least two sections each having three columns of ten rows each.

20 What I claim and desire to protect by Letters Patent is:

1. A universal score board for keeping score for card games which are scored in a different manner from each other, said board being divided 25 into four equal scoring sections spaced from each other, each section being provided with six parallel, longitudinal columns of ten sockets each, said sockets being in ten transverse rows parallel to 30 each other, indicia on the board successively numbering the rows, 1, 2, 3, 4, 5, 6, 7, 8, 9 and 0, there being a relatively wide longitudinal and a relatively wide transverse space extending from a central space separating the four sections from each other, four designating arrows in the central space, each section having one of the designating characters N, E, S and W, to each of which an arrow is pointed.

35 2. A universal score board for keeping score

40 for card games which are scored in a different manner from each other, said board being divided into four equal scoring sections spaced from each other, each section being provided with six parallel, longitudinal columns of ten sockets each,

45 said sockets being in ten transverse rows parallel to each other, indicia on the board successively numbering the rows 1, 2, 3, 4, 5, 6, 7, 8, 9 and 0, there being a relatively wide longitudinal and a relatively wide transverse space extending from

50 a central space separating the four sections from each other, four designating arrows in the central space, each section having one of the designating characters N, E, S and W, to each of which an arrow is pointed, the sections E and S being

55 positioned end to end forming one pair of sections which may be combined for scoring, the other sections N and W also being positioned end to end forming a second pair of sections which may be combined for scoring, the columns of sockets of

60 each pair of sections being in alignment with each other.

3. A universal score board for keeping score for card games which are scored in a different manner from each other, said board being divided into 65 four equal scoring sections spaced from each other, each section being provided with six parallel longitudinal columns of ten sockets each, said sockets being in ten transverse rows parallel to each other, indicia on the board successively

70 numbering the rows 1, 2, 3, 4, 5, 6, 7, 8, 9 and 0, there being a relatively wide longitudinal and a relatively wide transverse space extending from a central space separating the four sections from each other, four designating arrows in the central space, each section having one of the designating

characters N, E, S and W, to each of which an arrow is pointed, the sections E and S being positioned end to end forming one pair of sections which may be combined for scoring, the other sections N and W also being positioned end to end forming a second pair of sections which may be combined for scoring, the columns of sockets of each pair of sections being in alignment with each other, arrows at the ends of the columns of each pair of sections indicating the movement of the pegs during scoring of certain games.

4. A universal score board for keeping score for card games which are scored in a different manner from each other, said board being divided into four equal scoring sections spaced from each other, each section being provided with six parallel, longitudinal columns of ten sockets each, said sockets being in ten transverse rows parallel to each other, indicia on the board successively numbering the rows 1, 2, 3, 4, 5, 6, 7, 8, 9 and 0, there being a relatively wide longitudinal and a relatively wide transverse space extending from a central space separating the four sections from each other, four designating arrows in the central space, each section having one of the designating characters N, E, S and W, to each of which an arrow is pointed, the sections E and S being positioned end to end forming one pair of sections which may be combined for scoring, the other sections N and W also being positioned end to end forming a second pair of sections which may be combined for scoring, the columns of sockets of each pair of sections being in alignment with each other, arrows at the ends of the columns of each pair of sections indicating the movement of the pegs during scoring, the arrows at the ends of adjacent columns of one pair of sections being reversed relative to the other and so positioned in each pair of sections as to indicate scoring from the outside column to the inside column, there being an additional socket at the end of the inside column of each pair of sections for scoring

one hundred and twenty-one in each pair of sections.

5. A universal score board for keeping score for card games which are scored in a different manner from each other, said board being divided into four equal scoring sections spaced from each other, each section being provided with six parallel, longitudinal columns of ten sockets each, said sockets being in ten transverse rows parallel to each other, indicia on the board successively numbering the rows 1, 2, 3, 4, 5, 6, 7, 8, 9 and 0, there being a relatively wide longitudinal and a relatively wide transverse space extending from a central space separating the four sections from each other, four designating arrows in the central space, each section having one of the designating characters N, E, S and W, to each of which an arrow is pointed, the sections E and S being positioned end to end forming one pair of sections which may be combined for scoring, the other sections N and W also being positioned end to end forming a second pair of sections which may be combined for scoring, the columns of sockets of each pair of sections being in alignment with each other, there being an additional row of sockets at one end of the columns of a pair of sections spaced from the last row of sockets in the adjacent section.
